SKI BOOT

Frank D. Werner, Minneapolis, Ralph M. Darr, Excelsior, Marvin A. Luger, North St. Paul, and Paul S. Petersen, Minnetonka, Minn., assignors to Rosemount Engineering Company, Minneapolis, Minn., a corporation of Minnesota

Filed Mar. 31, 1965, Ser. No. 84,536

Term of patent 14 years

(Cl. D7—7)

FIG. 1 is a side elevational view of a ski boot embodying our new design;

FIG. 2 is a top plan view thereof;

FIG. 3 is a side elevational view of the side opposite that shown at FIG. 1;

FIG. 4 is a rear elevational view thereof;

FIG. 5 is a front elevational view thereof; and

FIG. 6 is a bottom plan view thereof.

The essential features of our design reside in the full line disclosure on the drawing.

We claim:

The ornamental design for a ski boot, as shown and described.
